[57] CLAIM

The ornamental design for a stove, as shown and described.

DESCRIPTION

FIG. 1 is a perspective view taken from the front and right side of a stove showing my new design;

FIG. 2 is a front elevational view thereof;

FIG. 3 is a rear elevational view thereof;

FIG. 4 is a right side elevational view thereof, the left side being a mirror image of the side shown; and

FIG. 5 is a top plan view thereof.

FIG. 1

FIG. 4

FIG. 5

FIG. 2

FIG. 3
